(57) **CLAIM**

The ornamental design for a drink lid with condiment well, as shown and described.

DESCRIPTION

FIG. 1 is a perspective view of a drink lid with condiment well showing my new design;

FIG. 2 is a top plan view thereof;

FIG. 3 is a bottom plan view thereof; and,

FIG. 4 is an elevational view of the rear, front, left and right sides thereof.

The broken lines in the drawings depict perforations.
